TUBULAR MAGAZINE FIREARM

Frank F. Burton, Mount Carmel, Conn., assignor,
by mesne assignments, to Western Cartridge
Company, a corporation of Delaware

Application October 8, 1938, Serial No. 233,940

6 Claims. (Cl. 42—17)

This invention relates to an improvement in tubular-magazine firearms and more particularly to means for securing the tubular-magazine of such firearms in place.

As will be apparent from the following considered in conjunction with the accompanying drawings, the present invention is concerned with a construction and organization of parts wherein the tubular-magazine located longitudinally in the buttstock is automatically aligned with the magazine-throat or cartridge-feeding passage forming a corporate part of the barrel-unit, when the said barrel-unit and stock-unit are coupled together.

Therefore, one of the main objects of the present invention is to provide a superior tubular-magazine firearm construction wherein simple, reliable and effective means is provided for properly locating the tubular-magazine with respect to a magazine-throat, or the like, incorporated in the receiver or frame of the firearm.

A further object of the present invention is to provide superior means, which may be produced at a low cost for manufacture, whereby the tubular-magazine is provided with self-aligning means for aligning the said tubular-magazine with respect to a magazine-throat, or the like, and which will automatically adjust itself with respect to the said magazine-throat to compensate for variation in manufacture as well as for warpage of the stock.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in side elevation of a take-down firearm embodying the present invention;

Fig. 2 is a broken view, partly in side elevation and partly in vertical central-longitudinal section of the firearm shown in Fig. 1;

Fig. 3 is a transverse sectional view taken on the line 3—3 of Fig. 2;

Fig. 4 is a broken side elevational view of the rear portion of the barrel-unit, detached;

Fig. 5 is a broken view, partly in side elevation and partly in vertical central-longitudinal section of the stock-unit, detached;

Fig. 6 is a top-plan view thereof;

Fig. 7 is a broken perspective view of the for-

ward portion of the tubular housing-member; and

Fig. 8 is a broken perspective view of the rear portion of the tubular housing-member.

The particular firearm herein chosen for illustration of the present invention is of the take-down type and includes a stock-unit generally designated by the reference character 10 and having a buttstock-portion 11 and a forestock-portion 12 integral therewith. Mounted upon the upper face of the said forestock-portion 12 is a barrel-unit generally designated by the reference character 13 and including a tubular receiver or frame 14 to the forward end of which is rigidly secured a barrel proper 15.

The particular character of the mechanism contained within the receiver or frame 14 forms no essential feature of the present invention, but, as shown in the drawings, the receiver 14 accommodates a reciprocating breech-bolt 16 visible through a longitudinal ejection-opening 17 formed in the side wall of the said receiver. The said breech-bolt 16 is provided with a bolt-operating handle 18 which extends outwardly through a longitudinal passage 19 also formed in the side wall of the receiver 14.

The receiver 14, in addition to containing part of the working mechanism (not shown) of the firearm, also contains a magazine-throat 20, or the like, formed with a cartridge-feeding passage and which at its rear end is provided with a cylindrical portion 21 for the purpose as will be hereinafter described. The magazine-throat just referred to, is rigidly secured in place in the receiver 14 in any suitable manner and is adapted to guide cartridges fed from the magazine to a position where they may be easily inserted into the cartridge-chamber of the firearm by the forward movement of the breech-bolt 16.

Adjacent the forward end of the receiver 14, the barrel 15 is provided on its under face with a depending stock attaching-lug 22 rigidly secured to the said barrel and fitting into a socket 23 extending downwardly from a longitudinal groove 24 formed in the upper face of the forestock-portion 12 of the stock-unit 10 for the reception of the barrel-unit 13. Extending upwardly through an escutcheon 25 mounted in the under face of the forestock-portion 12, is a screw 26 threaded into the lower portion of the lug 22.

As will be seen by reference to Fig. 2, the stock-unit 10 is provided with a relatively-deep clearance-groove 27 which extends downwardly from the rear portion of the bottom wall of the groove

24 and having a length substantially corresponding to the full length of the receiver 14. The bottom of the clearance-groove 27 is intersected by a vertical clearance-passage 28 through which extends a trigger 29 accommodated partly in the clearance-passage 28 and partly in the clearance-groove 27. The trigger 29 is pivoted upon a pivot-pin 30 mounted in the stock-unit 10 and has its finger-piece enclosed by the usual loop-like trigger-guard 31 secured to the under face of the said stock-unit.

The buttstock portion 11 of the stock-unit 10 is also provided with a longitudinal magazine-clearance passage 32 which at its inner or forward end intersects the longitudinal clearance-groove 27 in axial alignment with the magazine-throat 20 and which opens at its outer or rear end into a spherically-contoured recess 33. The recess 33 just referred to, accommodates the similarly-contoured portion 34 of a buttplate 36 secured to the rear face of the buttstock-portion 11 by means of screws 37—37. The provision of the spherically-contoured recess 33 and the similarly-formed portion 34 in the buttplate 36, results in the formation of a finger-clearance recess 35.

The magazine-clearance passage 32 is adapted to receive a tubular-magazine generally designated by the reference character 38 and substantially smaller in diameter than the said clearance-passage and in axial alignment with the magazine-throat 20 before referred to. The said magazine includes a tubular housing-member 39 and a tubular cartridge-receiving member 40 normally located within the said housing-member 39 but retractable rearwardly therefrom. The tubular-magazine 38 has its outer or rear portion 38a extending through the buttplate 36 and into the finger-clearance recess 35 in the rear face of the said buttplate where its member 40 is provided with a magazine-head 41 which is readily accessible for being grasped by the fingers of the user of the firearm for retracting and advancing the cartridge-receiving member 40. The said magazine-head is secured to the cartridge-receiving member 40 so as to form a unitary part thereof and together with the said cartridge-receiving member is releasably coupled to the housing-member 39 in any suitable manner permitting the ready retraction or removal of the said cartridge-receiving member from the housing-member 39.

Adjacent its outer or rear end, the housing-member 39 has rigidly secured thereto a magazine-retaining member or bushing 42 soldered or otherwise secured to the said housing-member. The magazine-retaining member just referred to, includes an externally-threaded annular sleeve 43 within which the housing-member 39 snugly fits and to which it is rigidly attached, and a flange 44. The flange 44 seats against the rear face of the spherically-contoured portion 34 of the buttplate 36 and is retained in place by an internally-threaded collar 45 which may seat at its rear edge against the front face of the spherically-contoured portion 34 of the buttplate 36, as is particularly well-shown in Fig. 2 of the drawings.

The housing-member 39 is provided at its forward or inner end with an upwardly-facing abutment-lip 46 of semi-circular form in cross-section and which is adapted to engage the under face of the cylindrical portion 21, before referred to, formed at the rear of the magazine-throat 20, as is particularly well-shown in Figs. 2 and

3 of the drawings. The abutment-lip 46 just referred to, is yieldingly held in engagement with the cylindrical portion 21 of the magazine-throat 20, by means of a helical spring 47 seated in an upwardly-opening pocket 48 extending downwardly from the clearance-groove 27 in the forestock-portion. The upper end of the said spring bears against the under face of the forward end of the housing-member 39 of the tubular-magazine 38. The spring 47 constantly urges the forward end 33b of the tubular-magazine 38 upwardly, the said magazine being restrained however, in proper axial alignment with the magazine-throat 20, by the engagement of the abutment-lip 46 with the cylindrical portion 21 of the said magazine-throat, which alignment ensures the proper passage into the magazine-throat of cartridges 49 contained within the cartridge-receiving member 40. The cartridges 49 are constantly being urged forwardly by a magazine-follower 50 under the tension of a spring 51 of the general type customarily employed in tubular-magazines.

From the foregoing it will be readily seen that the magazine will always be in proper alignment with the magazine-throat even in the event of warpage of the stock as the magazine is free to be deflected though still maintaining its proper position in respect to the said magazine-throat due to its own flexibility and the flexibility of the buttplate 36 and the connection of the magazine thereto. As will be readily apparent by reference to the drawings, the flexing of the magazine is permitted by the free fit of the tubular-magazine 38 in the magazine-clearance passage 32. The attaching of the magazine at the rear end thereof to the buttstock-portion leaves the forward or inner end free to be flexed for proper alignment with the magazine-throat as will hereinafter appear. It will be noted that by the construction employed, the tubular-magazine will align itself with respect to the magazine-throat when the barrel-unit is secured in coupled relationship to the stock-unit of the firearm.

By reference to Fig. 5 of the drawings it will be seen that when the barrel-unit 13 is uncoupled from the stock-unit 10 the tubular-magazine 38 will be deflected upwardly under the urge of the helical spring 47 or by the pre-set tension of the parts, from the position indicated by broken lines in the said figure (in which position the tubular-magazine is normally restrained by the magazine-throat 20), to the position shown in full lines in the figure referred to. When the stock-unit is separated from the barrel-unit 13, the upward deflection of the tubular-magazine will be limited by the pivot-pin 30, but the tubular-magazine may readily be deflected downwardly by the cylindrical portion 21 of the magazine-throat 20 when the barrel-unit 13 is installed in place upon the stock-unit 10.

When the barrel-unit 13 is installed in its proper position relative to the stock-unit, the cylindrical portion 21 of the magazine-throat 20 engages with the abutment-lip 46 with the result that the forward end of the tubular-magazine is depressed against the tension of the helical spring 47 which constantly urges the forward end of the said magazine upwardly thereby holding the abutment-lip 46 in engagement with the cylindrical portion 21 when the barrel-unit 13 is being installed upon the stock-unit 10.

By providing the structure above-described it will be apparent that the proper alignment of the tubular-magazine with respect to the bore or

other cartridge-feeding passage in the magazine-throat is assured by means of the flexible mounting of the said tubular-magazine and the helical spring which is preferably installed beneath the said magazine. It is possible, therefore, to leave a sufficient gap between the rear end of the magazine-throat and the forward end of the magazine proper to allow for variation in manufacture as well as in providing compensation for warpages or other irregularities in the stock itself.

Another advantage in employing the construction shown and described is that the barrel-unit comprising the receiver and barrel proper may be readily uncoupled from the stock-unit for transportation, cleaning or the like and then reinstalled upon the stock-unit with the magazine properly aligned with the magazine-throat without any special adjustments or care on the part of the user of the firearm.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A takedown tubular-magazine firearm-structure including in combination: a barrel-unit having a barrel and also a member provided with a cartridge-feeding passage located below the said barrel and constructed and arranged to register with the cartridge-delivery opening of a tubular-magazine, the said member also being provided with a magazine-engaging abutment engageable with a stop-abutment of a tubular-magazine; a stock-unit extending beneath the said barrel-unit; a tubular-magazine carried by the said stock-unit with capacity for lateral movement toward and away from the said barrel-unit, the said tubular-magazine being provided with a cartridge-delivery opening normally registering with the cartridge-feeding passage in the said member of the barrel-unit, the said tubular-magazine also being provided with a stop-abutment positioned to engage with the magazine-engaging abutment of the said member of the barrel-unit when the cartridge-delivery opening of the said tubular-magazine registers with the cartridge-feeding passage in the said member of the barrel-unit; and spring-means pressing the said tubular-magazine laterally to yieldingly engage the stop-abutment thereof with the magazine-engaging abutment of the said member of the barrel-unit to thereby maintain the cartridge-delivery opening of the said tubular-magazine in registry with the cartridge-feeding passage in the said member of the barrel-unit.

2. A takedown tubular-magazine firearm-structure as defined in claim 1 and in which the spring-means specified is in the form of a compression-spring thrusting in opposite directions respectively against the said stock and against the said tubular-magazine.

3. A takedown tubular-magazine firearm-structure including in combination; a barrel-unit having a barrel and also a member provided with a cartridge-feeding passage located below the said barrel and constructed and arranged to register with the cartridge-delivery opening of a

tubular-magazine, the said member also being provided with a downwardly-facing magazine-engaging abutment engageable with an upwardly-facing stop-abutment of a tubular-magazine; a stock-unit extending beneath the said barrel-unit; a tubular-magazine carried by the said stock-unit with capacity for lateral movement toward and away from the said barrel-unit, the said tubular-magazine being provided with a cartridge-delivery opening normally registering with the cartridge-feeding passage in the said member of the barrel-unit, the said tubular-magazine also being provided with an upwardly-facing stop-abutment positioned to engage with the downwardly-facing magazine-engaging abutment of the said member of the barrel-unit when the cartridge-delivery opening of the said tubular-magazine registers with the cartridge-feeding passage in the said member of the barrel-unit; and spring-means pressing the said tubular-magazine upwardly to yieldingly urge the upwardly-facing stop-abutment thereof into engagement with the downwardly-facing magazine-engaging abutment of the said member of the barrel-unit to thereby maintain the cartridge-delivery opening of the said tubular-magazine in registry with the cartridge-feeding passage in the said member of the barrel-unit.

4. A takedown tubular-magazine firearm-structure as defined in claim 3 and in which the spring-means specified is in the form of a compression-spring thrusting downwardly upon the said stock and upwardly against the said tubular-magazine.

5. A takedown tubular-magazine firearm-structure including in combination: a barrel-unit having a barrel and also a receiver provided with a cartridge-feeding passage located below the said barrel and constructed and arranged to register with the cartridge-delivery opening of a tubular-magazine, the said receiver also being provided with a magazine-engaging abutment engageable with a stop-abutment of a tubular-magazine; a stock-unit extending beneath the said barrel-unit; a tubular-magazine carried by the said stock-unit with capacity for lateral movement toward and away from the said barrel-unit, the said tubular-magazine being provided with a cartridge-delivery opening normally registering with the cartridge-feeding passage in the said receiver of the barrel-unit, the said tubular-magazine also being provided with a stop-abutment positioned to engage with the magazine-engaging abutment of the said receiver of the barrel-unit when the cartridge-delivery opening of the said tubular-magazine registers with the cartridge-feeding passage in the said receiver; and spring-means pressing the said tubular-magazine laterally to yieldingly urge the stop-abutment thereof into engagement with the magazine-engaging abutment of the said receiver of the barrel-unit to thereby maintain the cartridge-delivery opening of the said tubular-magazine in registry with the cartridge-feeding passage in the said receiver of the barrel-unit.

6. A takedown tubular-magazine firearm-structure as defined in claim 5 and in which the spring-means specified is in the form of a compression-spring thrusting in opposite directions respectively against the said stock and against the said tubular-magazine.
